SHOE

George Anson, Island Park, N. Y.

Application May 19, 1943, Serial No. 487,637

2 Claims. (Cl. 36—15)

This invention relates to shoes and more particularly to a construction of shoe which will be durable, economical to manufacture and will permit the shoe to be easily and quickly rebuilt when the sole and heel become worn.

Another object of this invention is the provision of a shoe construction which provides quick attachable means for the sole and heel conveniently operable by anyone not skilled in shoe making so that the sole or heel or both may be renewed when worn by replacements or renewal parts substituted therefor without the possibility of injury to the stitchings or any parts which go to make up the shoe.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a shoe constructed in accordance with my invention.

Figure 2 is a fragmentary longitudinal sectional view illustrating the quick detachable means of securing the sole and heel in place on the midsole of the shoe.

Figure 3 is a bottom plan view illustrating the midsole equipped with the parts of the quick detachable means which remain as a part of the midsole at all times.

Figure 4 is a plan view illustrating the outer sole and the parts of the quick detachable means carried thereby.

Figure 5 is a plan view illustrating the part of the quick detachable means carried by the lower part of the heel construction.

Figure 6 is a sectional view taken on the line 6—6 of Figure 5.

Figure 7 is a transverse sectional view taken through the midsole and outer sole showing the quick detachable means.

Figure 8 is an exploded sectional view showing the connecting plates employed between the outer sole and the midsole.

Referring in detail to the drawings, the numeral 5 indicates the shoe upper, 6 the inner sole, 7 the welt which protrudes not less than $\frac{1}{16}$ inch beyond the upper, 8 the midsole, 9 the outer sole and 10 the heel construction including upper and lower sections 11 and 12.

The upper is of a conventional construction and design and is secured to the welt by stitch-

ing. The midsole 8 is secured to the welt by stitching arranged exteriorly of the upper. The upper section 11 of the heel construction is secured to the midsole 8 by fasteners 14. The fasteners 14 may be of any suitable construction, preferably in the form of rivets.

The quick detachable means for the outer sole to the midsole and the lower section to the upper section of the heel construction 10, is indicated 10 generally by the character 15. Said quick detachable means 15 will permit anyone unskilled in shoemaking to easily and quickly attach and detach the outer sole and the lower heel section when worn so that like renewal parts may be 15 substituted therefor, rebuilding or reconditioning the shoe for further practical use.

The quick detachable means employed between the outer sole and midsole includes plates 16 and 17 of metallic construction. Fasteners 13 20 secure the plate 16 to the midsole, while rivets or like fasteners 18 secure the metallic plate 17 to the outer sole, the rivets 18 being countersunk in the outer sole.

The plate 16 is provided with slots 19 and 25 pockets 20 partially overlying said slots. The pockets and slots are preferably three in number and are arranged in the plate 16, as shown in Figure 3, with the pockets opening toward the toe of the midsole with one of the slots opening 30 outwardly through an edge of said plate 16 at the toe of the midsole.

The plate 17 is provided with slots 21 to receive the pockets 20 of the plate 16 and the plate 17 has struck therefrom tongues 22 aligning with 35 the slots 21 and extending in the direction of the heel of the shoe so that in the application of the plate 17 to the plate 16, the plate 17 is moved rearwardly or in an endwise direction toward the heel of the shoe bringing the tongues 22 into 40 the pockets 20 and the latter into the slots 21, thereby efficiently anchoring the plates 16 and 17 together.

To prevent the tongues 22 from moving out of the pockets by an endwise movement of the outer sole with relation to the midsole, fasteners 23 45 are employed and are located at the instep of the shoe and extend through the outer sole and midsole. The fasteners 23 are in the form of threaded headed studs kerfed to receive a suitable tool and are threaded into nuts or similar elements 24. A metallic reinforcing strip 25 is arranged across the outer sole with the fasteners 23 extending therethrough.

Thus it will be seen that in order to remove 50 the outer sole, it is only necessary to remove the

fasteners 23 and slide the outer sole endwise toward the toe of the shoe relative to the midsole so that the tongues move out of the pockets of the plates 16 and 17.

As clearly shown in Figures 1 and 2 of the drawings the plates 15 and 16 do not extend the full lengths of the outer sole and the midsole and the space resulting therefrom will be filled by a filler strip of leather or any other suitable material and is secured in place in any well known manner.

The quick detachable means 15 employed in the heel construction consists of metallic plates 27 and 28. The metallic plate 27 has struck therefrom a plurality of tines 29 embedded in the lower section 12 of the heel construction. The plate 28 is secured to the upper heel section by the fasteners 14. A channel or groove 30 is provided in the upper heel section over which lies the plate 28. The plate 27 has struck therefrom tongues 31 extending rearwardly of the heel construction. One of the tongues is adapted to pass through a slot 32 provided in the plate 28 and is slotted, as shown at 33, the other tongue 31 interlocking with the plate 28 by entering the forward end of the channel or groove 30 when the heel sections 11 and 12 are assembled by sliding the heel section 12 rearwardly with respect to the heel section 11.

Suitably secured in the channel or groove 30 is a retaining nut 35 in which is threaded a fastener 36 constructed similar to the fasteners 23. The head of the fastener 36 is countersunk in the outer heel section and passes through openings provided in the plates 27 and 28. The fastener 36 prevents endwise movement of the lower heel section relative to the upper heel section, consequently maintaining the tongues of the plate 27 in interlocking connection with the plate 28 preventing separation of the heel sections.

Therefore, it will be seen that to remove the heel section 12, it is only necessary to remove the fastener 36 and slide the heel section 12 forwardly relative to the section 11.

A shoe constructed in accordance with the foregoing will be extremely serviceable and can be rebuilt by anyone having replacement parts

without the knowledge of shoemaking. The reconditioning of the shoe due to its construction can be carried out without danger of injury to any of the unworn parts of the shoe such as the upper, welt and midsole and upper heel section of the heel construction.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a shoe construction including a welt of an upper and a midsole, stitching securing the midsole to the welt exteriorly of the upper, an outer sole for the midsole, metallic plates arranged between the outer sole and the midsole, fasteners securing one of said plates to the midsole, fasteners securing the other plate to the outer sole both of said plates having openings therein, pockets formed on one of said plates at one edge of the openings therein and adapted to enter the openings of the other plate, and tongues struck from the other plate adjacent the openings therein and bent upon the plate partially over the adjacent openings to fit in said pockets.

2. In a shoe construction including a welt of an upper and a midsole, stitching securing the midsole to the welt exteriorly of the upper, an outer sole for the midsole, metallic plates arranged between the outer sole and the midsole, fasteners securing one of said plates to the midsole, fasteners securing the other plate to the outer sole both of said plates having openings therein, pockets formed on one of said plates at one edge of the openings therein and adapted to enter the openings of the other plate, tongues struck from the other plate adjacent the openings therein and bent upon the plate partially over the adjacent openings to fit in said pockets, and removable fasteners extending through the midsole and outer sole to prevent the midsole from moving lengthwise of the midsole and allowing the tongues to move out of the pockets.

GEORGE ANSON.
